US0D1050112S

(12) **United States Design Patent** (10) **Patent No.:** **US D1,050,112 S**
(45) **Date of Patent:** **** Nov. 5, 2024**

(54) **SMART WATCH WITH EARBUDS**

(71) Applicant: **Shenzhen Diewei Technology Co., Ltd.**, Shenzhen (CN)

(72) Inventor: **Linwei Li**, Xianning (CN)

(**) Term: **15 Years**

(21) Appl. No.: **29/933,298**

(22) Filed: **Mar. 19, 2024**

(30) **Foreign Application Priority Data**

Feb. 29, 2024 (CN) 202430103283.7
